UNITED STATES PATENT OFFICE.

REUBEN W. NORTON, OF HASTINGS, NEBRASKA.

ENDLESS CONVEYER.

1,108,386.

Specification of Letters Patent. Patented Aug. 25, 1914.

Application filed March 2, 1914. Serial No. 822,621.

To all whom it may concern:

Be it known that I, REUBEN W. NORTON, a citizen of the United States, residing at Hastings, in the county of Adams and State 5 of Nebraska, have invented certain new and useful Improvements in Endless Conveyers, of which the following is a specification, reference being had to the accompanying drawings.

10 This invention comprehends certain new and useful improvements in endless conveyers and has for its primary object to provide a device of this character which will be of extremely simple construction, as well 15 as highly efficient and effective in use.

Another object is to provide a device of this character, in which the framework will be strong and durable and may be supported upon an incline.

20 A further object is to provide a device of this character in which the movable member will be composed of a pair of sprocket chains connected by cross bars to which is secured a flexible endless member composed 25 of canvas or other suitable material.

A further object is to provide a device of 30 this character in which the endless flexible member, cross bars, and endless sprocket chains may be securely connected to one another, whereby said parts will be retained in their proper relative positions.

With the above and other objects in view, my invention consists in certain novel constructions, combinations, and arrangements 35 of parts to be hereinafter more fully described, claimed, and illustrated in the accompanying drawings, in which

Figure 1 is a plan view of my complete device; Fig. 2 is a side elevation of the device. Fig. 3 is a fragmentary longitudinal section of the upper end of the conveyer. Fig. 4 is a fragmentary section of the lower end of the conveyer. Fig. 5 is a transverse section thereof.

45 Referring more specifically to the drawings in which similar reference characters designate corresponding parts throughout the several views, 1 designates the main longitudinal members of the frame which are 50 connected by the transverse frame members 2 which are secured against the under face of said longitudinal frame members 1, certain of said transverse frame members 2 having their opposite ends extended beyond 55 the longitudinal frame members 1 and connected with the latter by the brace strips 3

which have their opposite ends bent outwardly and secured upon the extended ends of said transverse frame members and upon the upper portions of the longitudinal 60 frame members 1. The lower longitudinal frame members 4 are positioned beneath the main longitudinal frame members 1 and parallel with the latter, said lower longitudinal frame members 4 being engaged 65 against the lower faces of the transverse frame members 2. U-shaped brace members 5 have their opposite legs secured to the outer faces of the lower longitudinal frame members 4 while the free extremities of said 70 legs are turned outwardly at right angles and secured to the transverse frame members 2, thereby securely bracing the lower longitudinal frame members. The main portions of the U-shaped brace members 5 75 are connected by the thin longitudinal metallic strips 6 which are secured to the upper faces of the main portions of said U-shaped brace members 5, adjacent the legs of the latter. The U-shaped brace members 5 and thin longitudinal metallic strips will 80 serve to limit downward movement or sliding of the lower or under portions of the movable members or the conveyer, as will be later clearly apparent.

85 Secured to the upper faces of the transverse frame members 2 are the thin upper longitudinal metallic strips 7 over which the movable continuous flexible member of the conveyer moves, said strips 7, together 90 with the transverse frame members 2, serving to limit downward movement of the upper portion of said flexible member and prevent sagging of the same during operation of the device, as will also be later 95 clearly apparent.

The free ends of the thin upper longitudinal metallic strips 7 at the upper or discharge end of the conveyer, are curved downwardly, as shown at 8, while the free 100 ends of the lower longitudinal metallic strips 6 are also curved downwardly and secured to the main portion of the large U-shaped brace members 5 at the upper end of said conveyer, said large U-shaped brace 105 members 5 having longer legs than the other U-shaped brace members 5, as clearly shown in the drawings. By curving the upper ends of the strips 6 and 7 in this manner, danger of the movable members of the conveyer becoming caught upon the ends of 110 said strips, is eliminated.

The frame is supported in proper position above the ground by the forward legs 9 secured by their upper ends in the sockets 10 on the outer faces of the main longitudinal frame members 1 near the forward ends thereof and by the long legs 11 adjustably engaged through the open sockets 12 also secured to the outer faces of the main longitudinal frame members 1, it being understood that a plurality of open sockets 12 are provided and arranged in pairs at spaced distances throughout the length of the frame. It will also be understood that the long legs 11 are provided with suitable perforations 13 throughout their length, to receive the pins 14, whereby said pins may be positioned in the proper perforations 13 beneath the open sockets 12 to support the frame upon the desired incline. When desired, the rear supporting legs 15 may also be employed, each rear leg being composed of a pair of members crossed adjacent their upper ends and connected by the pivot pin 16, said crossed members being adapted to receive the opposite ends of the rod 17 secured transversely through the main longitudinal frame members 1 adjacent the rear ends of the latter, it being understood that the crossed members are connected adjacent their lower ends by the connecting wire 18 or the like to limit outward movement or spreading of said lower ends of the crossed members.

The bearing blocks 19 are secured to the outer faces of the main longitudinal frame members 1, at the opposite ends thereof and the shafts 20 are mounted for rotation in said bearing blocks, said shafts 20 having the sprocket wheels 21 mounted thereon between the main longitudinal frame members 1 and one of said shafts being also provided with a sprocket wheel 23 outwardly of one of said main longitudinal frame members for engagement by a chain 23' connected to the sprocket wheel 23" mounted on the drive shaft 24 which has one end squared to receive a suitable crank (not shown), by means of which the drive shaft 24 may be rotated.

Engaged around the corresponding sprocket wheels 21 upon the shafts 20, are the endless sprocket chains 25 which are connected by the cross bars 26, the endless flexible member or apron 27 being secured to the under faces of the cross bars 26 by the securing strips 28 positioned against the under face of the endless flexible member or apron and fastened to the cross bars, with which said securing strips are parallel, thereby securely clamping the endless flexible member or apron 27 between said cross bars 26 and securing strips 28. By connecting the movable members of the conveyer in this manner, said movable members will be at all times retained in proper relation to one another during operation of the device and the

cross bars 26 will serve to retain material in proper position upon the endless flexible member or apron 27 while said material is being elevated to the upper end of the conveyer. As the material reaches the upper end of the conveyer, it will travel over the same, the guard or hood 29 serving to guide the material over the upper end of the conveyer, said guard or hood comprising a curved plate 30 having its opposite longitudinal edges secured upon the curved arms 31 which are hinged to the upper face of the main longitudinal frame members 1 at spaced distances from the upper ends of the latter, as shown at 32, and having their lower faces cut away, as shown at 33, in order that the greater portions of said arms may rest upon the upper faces of the main longitudinal frame members 1 while the free ends of said curved arms 31 project over the upper ends of said main longitudinal frame members 1.

To guide the material toward the longitudinal center of the endless flexible member or apron 27, I have provided the inclined guide members 34 at the forward end of the frame and secured upon the main longitudinal frame members 1, said guide members 34 being inclined downwardly and inwardly toward the longitudinal center of the endless flexible member or apron 27, as will be readily understood. I have also provided a stop plate 35 at the lower end of the frame, said plate being secured to the lower ends of the inclined guide members 34 to prevent any material from falling off of the lower end of the conveyer.

From the foregoing, it will be apparent that I have provided an endless conveyer or elevator which may be of extremely simple and cheap construction but which will be strong and durable in use and which will be especially adapted for use in elevating dirt during operation of digging an underground silo or the like and which is also especially adapted for elevating ensilage and conveying said ensilage to the desired point.

While I have shown the preferred embodiment of my invention, it will be understood that minor changes in the details of construction and arrangement of parts may be made within the scope of the appended claims without departing from the spirit of my invention or sacrificing any of the advantages of the same.

What is claimed is:

1. A device of the class described comprising a frame including upper longitudinal bars, transverse bars connected to the lower faces of the longitudinal bars, lower longitudinal bars positioned against the lower faces of the transverse bars, transverse brace members secured to the lower faces of the lower bars and having their ends extending upwardly and secured to the transverse bars,

an endless conveyer member mounted in the frame and having its stretches disposed above and below the transverse bars, and means carried by said transverse bars and said transverse brace members to prevent sagging of the stretches of the conveyer member.

2. A device of the class described comprising a frame including upper longitudinal bars, transverse bars secured against the lower faces of said upper bars, lower longitudinal bars positioned against the lower faces of the transverse members, transversely extending brace members secured against the lower edges of the lower longitudinal frame members, longitudinal brace strips connected

to the upper faces of the transverse brace strips and to the upper faces of the transverse bars, an endless conveyer member mounted in the frame and extending around 20 said transverse bars, said longitudinal brace strips being adapted to support the upper and lower stretches of the conveyer member to prevent the same from sagging, and means for supporting the frame in an elevated position.

In testimony whereof I hereunto affix my signature in the presence of two witnesses.

REUBEN W. NORTON.
